SOUND APPARATUS

Robert Longfellow Williams, Newton, Mass., assignor to Submarine Signal Company, Boston, Mass., a corporation of Maine

Original application May 23, 1929, Serial No. 365,385. Divided and this application August 11, 1930, Serial No. 474,482

4 Claims. (Cl. 177—7)

This application is a division of my application Serial No. 365,385, filed May 23, 1929.

The present invention relates to means for creating sound waves in any medium, but more particularly in air.

There are many types of sound generators. For fog or bad weather signaling, it has been common practice to use air sirens, steam or air whistles. A newer type of sound producer for fog signaling is the electromagnetic and electrodynamic type, sometimes called air oscillators.

These air oscillators are usually designed to produce a sound of a pure tone and are found to carry further distances on account of the pure note which they produce. This is due, it is believed, to the fact that in the propagation of a pure tone, the phases do not become mixed, so that there is less wattless energy oscillating back and forth in the medium. Besides this, the ear very readily detects a pure tone, even though it is weak, because of its accumulative effect in building up a substantial vibration.

It is desirable, therefore, to have a pure tone, and for that reason the air oscillators have been given a definite oscillating resonant frequency and have been operated at that resonant frequency.

Air oscillators are operated by alternating current sources delivering power at the frequency at which the sound is to be generated. While the generators remain at the frequency at which the sound is to be produced, the maximum energy may be drawn from the electric system, but when the frequency of the electric system falls off resonance, as when a change in voltage occurs or when other changes take place, the maximum amount of energy cannot be absorbed and radiated by the air oscillator.

The temporary variations causing temporary fluctuations of the power emitted by air oscillators is not very serious, but when the variations are more than temporary, the power output of the air oscillators may be considerably diminished and consequently its range of audibility may be affected. This difficulty may be overcome either by having a system which has no particular resonance or by having a system in which the resonance may be controlled, or by a combination of the two methods.

Where the system has no marked resonance, it has been found difficult in some cases to produce great enough amplitudes to radiate the power desired with the size of radiator available for use. To overcome this objection with-

out the introduction of a tuned system, I employ a lever arrangement whereby the amplitude of the electrical system is multiplied at the sound radiating element.

To increase further the power radiated, the radiating member may be loaded by putting a horn or an adjustable resonating chamber before it. The horn, while having some resonant characteristics, is not sharply marked and the adjustable resonant chamber being adjustable within the range which the frequency may vary, the system as a whole can readily be made to radiate at its maximum output and allow reception of the sound signal at uniform distances practically all the time.

The invention will be best understood from a consideration of the following description and drawing in which

Figure 1 shows a section of my invention; Figures 2 and 3 show details of Figure 1; and Figure 4 shows a modification of a detail in Figure 1.

In Figure 1 the electrical system is of the Fessenden oscillator type as shown in the Fessenden Patent No. 1,167,366. Here the system comprises a core 3, an outer shell 1 composed of two parts bolted together at the flange 5 by bolts 6. Within the shell 1 is a coil 2 in which direct current flows to magnetize the air gap between the core 3 and the shell 1. Wound upon the core 3 is a winding 7, through which the alternating current flows for producing alternating current in the copper or aluminum tube 8. The change of current in the tube 8 causes it to move back and forth longitudinally in the air gap and impart sound vibrations to the sound radiating element.

The system shown produces motion both ways and therefore needs no springs or restoring forces, as in some systems, to bring the oscillating elements back to their starting or normal positions.

The central core 3 is held in position by ears or corners 9, 9, 9, 9 to the outer shell 1. Mounted on these ears are bearing pieces 10, forked in shape as shown in Figure 3. These pieces support the levers 11 at their ends by the pins 12 which pass through the levers and the bearing pieces. The levers 11 have their other ends resting in a groove 13 in the collar piece 14. The levers 11 are spaced radially from the central collar piece 14, as shown in Figure 2, where there are three in number. There may be more or less, in accordance with the most suitable design. The center collar 14 carries the

spider 15, to which the radiating element 16 is attached.

The top of the shell 1 is closed by the horn element 17 in the throat of which the radiating piston 16 works. Closing the edge between the radiating piston and the horn is a disc of rubber or other suitable material 18, clamped to the member 16 and to the wall for preventing the pressure release to the back of the radiating element and also to protect the inside mechanism from moisture and bad weather.

At the lower end of the oscillator are provided similar levers 11 mounted and fastened in the same manner as the levers at the top except that there is no radiating member attached to the collar 14. A radiating member may be used here, however, if it is desired to radiate from both ends.

The copper tube 8, which may be of some other suitable conducting material if desired, has projecting arms 19 which may have knifed edge ends 20 fitting into cuts in the levers 11 near the pivoted ends, as shown in Figure 1.

When the system is assembled, the various elements are put together and the nuts 21, 21 at opposite ends of the rod 22 are tightened until the desired pressure is exerted between the levers 11 and the arm 19 extending from the copper tube. This also tensions the levers 11 against the bearing support 12 so that the system is a unified structure.

The tube 8 and the arms 19 have only a small motion, but at the free end of the levers 11, at the collar 14, the motion is multiplied in the ratio of the length of the lever to the distance between the point of bearing of the arm 19 and the point of pivot. The center collar has, therefore, an increased amplitude which is imparted to the radiating element 16 through the spider 15.

The system as shown in Figure 1 has no marked resonance so that if the frequency of the alternating current impressed upon the coil 7 should change, due to change in the frequency of the electrical system, as sometimes takes place, there will be no appreciable diminution of energy radiated from the device.

In place of using a pivoted lever system, as shown in Figure 1, a system as shown in Figure 4 may be used, where the levers 50 may have their ends firmly clamped by means of the clamping member 51 and bolt 52. The other ends of the levers may also be clamped to the rod 32 by means of the clamping washers 53 and 54 and the nut 55, threading on the rod 22.

Having now described my invention, I claim:

1. A means for producing sound waves comprising an electrically oscillated shell element, a plurality of levers positioned at opposite ends of said shell and extending from a position outside of the shell element towards the shell center, means pivoting the outer extremities of said levers adjacent opposite ends of the shell, means for connecting the inner ends of said levers and exerting a pressure between the levers positioned at opposite ends of the shell, a sound radiating element and means connecting said sound radiating element with the inner ends of said levers and means for oscillating said shell element. 80

85

90

2. A means for producing sound waves comprising an electrodynamic oscillating mechanism including a cylindrical moving element, a plurality of levers, means for fixing and supporting said levers, at opposite ends of said cylindrical element and means cooperating with said levers for firmly supporting said cylindrical element between said levers, including means forming a part of said cylindrical element and projecting to said levers, and a radiating element 100 attached to the means cooperating with said levers. 95

3. A means for producing sound waves comprising an electrodynamic oscillating mechanism, including an enclosed moving element, a 105 plurality of levers, means for fixing and supporting one set of ends of the levers externally adjacent to opposite ends of said moving element and bearing on the same at points near the lever supporting means, and means holding the 110 other ends of the opposite groups of levers together to exert pressure on the bearing points between the levers and the moving element, and radiating means attached to said last named means. 115

4. A means for producing sound waves comprising an electrical oscillating mechanism including an enclosed moving element, a plurality of levers, means for fixing and supporting one set of ends of the levers externally adjacent to 120 opposite ends of said moving element and bearing on the same at points near the lever supporting means, and means holding the other ends of the opposite groups of levers together to exert pressure on the bearing surfaces between the 125 levers and the moving element, and a radiating means attached to the point of greatest motion of the moving system. 130
